CLAIM

The ornamental design for a combined liquid dispenser and spigot, as shown and described.

DESCRIPTION

FIG. 1 is a front elevational view of a combined liquid dispenser and spigot showing my new design;

FIG. 2 is an enlarged front elevational view of a spigot shown alone for clarity of illustration;

FIG. 3 is a rear elevational view of FIG. 1;

FIG. 4 is a rear elevational view of FIG. 2;

FIG. 5 is a right side elevational view of FIG. 1, the left side being a mirror image;

FIG. 6 is a right side elevational view of FIG. 2, the left side being a mirror image;

FIG. 7 is a top plan view of FIG. 1;

FIG. 8 is a top plan view of FIG. 2;

FIG. 9 is a bottom plan view of FIG. 1;

FIG. 10 is a bottom plan view of FIG. 2; and,

FIG. 11 is a top front perspective view of FIG. 1.

The broken lines showing the bottle are for illustrative purposes only and form no part of the claimed design.
